UNITED STATES PATENT OFFICE.

RUDOLPH GNICHWITZ, OF ASHBOURNE, PENNSYLVANIA, ASSIGNOR TO
MATHER MANUFACTURING CO., OF PHILADELPHIA, PENNSYLVANIA.

DESIGN FOR A FONT OF PRINTING-TYPE.

SPECIFICATION forming part of Design No. 29,080, dated July 19, 1898.

Application filed June 20, 1898. Serial No. 684,003. Term of patent 7 years.

To all whom it may concern:

Be it known that I, RUDOLPH GNICHWITZ, a citizen of the United States, residing at Ashbourne, in the county of Montgomery and State of Pennsylvania, have invented and produced a certain new, original, and useful Design for a Font of Outline Old-Face Type, of which the following is a full, clear, and exact description.

10 My design is a modification of the "Old-English" or "black-letter" type, constructed in outline essentially as shown in the accompanying drawing, which forms a part hereof.

15 In the said drawing I have shown a font of type comprising lower-case letters, diphthongs, digraphs, and trigraphs, upper-case, points, dollar-mark, numerals, and English-pound (money) mark, these being the usual characters which go to make up a font of type.

20 As shown in the drawing, the leading or material feature of my design consists in the formation of the characters in outline, the characters being broad relatively to their

length. The kerns or vertical projections of such letters as b, h, k, l, p, and q of the lower case are forked, and the ceriphs are oval or approximately oval in some instances and angular in other instances.

25 I have designated my type as "Old Face" because it is a modification of the Old-English or black-letter types which have long been in common use; but my design differs from these old and common styles of type as well in general appearance or conformation 30 as in the essential fact that the characters are in outline, the difference appealing rather to the eye than being capable of further and detail verbal description.

35 What I claim is—

40 The design for a font of printing-type, substantially as shown and described.

In testimony whereof I have hereunto set my hand this 2d day of June, A. D. 1898.

RUDOLPH GNICHWITZ.
